(57) **CLAIM**

The ornamental design for a drying machine filter box, as shown and described.

DESCRIPTION

FIG. 1 is a perspective front view of a drying machine filter box showing my new design;

FIG. 2 is a perspective back view thereof;

FIG. 3 is a front view thereof;

FIG. 4 is a back view thereof;

FIG. 5 is a right side view thereof;

FIG. 6 is a left side view thereof;

FIG. 7 is a top view thereof;

FIG. 8 is a bottom view thereof; and,

FIG. 9 is a perspective bottom view thereof.

The broken lines shown on the drying machine filter box are included for the purpose of illustrating portions of the article that form no part of the claimed design.

1 Claim, 9 Drawing Sheets
